(57) **CLAIM**

The ornamental design for a prying bar, as shown and described.

DESCRIPTION

FIG. 1 is a perspective view of a prying bar showing my new design;

FIG. 2 is a front view thereof;

FIG. 3 is a left view thereof;

FIG. 4 is a right view thereof;

FIG. 5 is a top view thereof;

FIG. 6 is a bottom view thereof; and,

FIG. 7 is a perspective view of the prying bar showing my new design and shows the prying bar connected to a handle. The broken lines depict portions of the prying bar in which the design is embodied that are not considered part of the claimed design.
